UNITED STATES PATENT OFFICE

108,535

DESIGN FOR A SERVICE STATION BUILDING OR THE LIKE

John F. Cheney, West Palm Beach, Fla.

Application December 16, 1936, Serial No. 66,571

Term of patent 7 years

To all whom it may concern:

Be it known that I, John F. Cheney, a citizen of the United States, residing at West Palm Beach, in the county of Palm Beach and State of Florida, have invented a new, original, and ornamental Design for a Service Station Building or the like, of which the following is a specification, reference being had to the accompanying drawing, forming part thereof, and in which:

Figure 1 is a view in perspective of a service station showing my design.

Fig. 2 is a view in top plan.

Fig. 3 is a view in side elevation.

I claim:

The ornamental design for a service station building or the like, as shown.

JOHN F. CHENEY.
